(57) **CLAIM**

We claim the ornamental design for a mattock tool, as shown and described.

DESCRIPTION

FIG. 1 is a top perspective view of a first embodiment of a mattock tool showing our new design;

FIG. 2 is a bottom perspective view of the mattock tool of FIG. 1;

FIG. 3 is a front view of the mattock tool of FIG. 1, the opposing rear view being identical thereto;

FIG. 4 is a right side view of the mattock tool of FIG. 1;

FIG. 5 is a left side view of the mattock tool of FIG. 1;

FIG. 6 is a top view of the mattock tool of FIG. 1;

FIG. 7 is a bottom view of the mattock tool of FIG. 1;

FIG. 8 is a top perspective view of a second embodiment of a mattock tool showing our new design;

FIG. 9 is a bottom perspective view of the mattock tool of FIG. 8;

FIG. 10 is a front view of the mattock tool of FIG. 8, the opposing rear view being identical thereto;

FIG. 11 is a right side view of the mattock tool of FIG. 8;

FIG. 12 is a left side view of the mattock tool of FIG. 8;

FIG. 13 is a top view of the mattock tool of FIG. 8;

FIG. 14 is a bottom view of the mattock tool of FIG. 8;

FIG. 15 is a top perspective view of a third embodiment of a mattock tool showing our new design;

FIG. 16 is a bottom perspective view of the mattock tool of FIG. 15;

FIG. 17 is a front view of the mattock tool of FIG. 15, the opposing rear view being identical thereto;

FIG. 18 is a right side view of the mattock tool of FIG. 15;

FIG. 19 is a left side view of the mattock tool of FIG. 15;

FIG. 20 is a top view of the mattock tool of FIG. 15;

FIG. 21 is a bottom view of the mattock tool of FIG. 15;

FIG. 22 is a top perspective view of a fourth embodiment of a mattock tool showing our new design;

FIG. 23 is a bottom perspective view of the mattock tool of FIG. 22;

FIG. 24 is a front view of the mattock tool of FIG. 22, the opposing rear view being identical thereto;

FIG. 25 is a right side view of the mattock tool of FIG. 22;

FIG. 26 is a left side view of the mattock tool of FIG. 22;

FIG. 27 is a top view of the mattock tool of FIG. 22; and,

FIG. 28 is a bottom view of the mattock tool of FIG. 22. The dash-dash broken lines in the drawings illustrate portions of the mattock tool and form no part of the claimed design. The dot-dot-dash broken lines in the drawings define the bounds of the claim and form no part thereof. The shade
